UNITED STATES PATENT OFFICE.

ISAAC L. STOVER, OF CENTRALIA, ILLINOIS.

CAR-COUPING.

SPECIFICATION forming part of Letters Patent No. 279,201, dated June 12, 1883.

Application filed April 9, 1883. (No model.)

To all whom it may concern:

Be it known that I, ISAAC L. STOVER, a citizen of the United States, residing at Centralia, in the county of Marion and State of Illinois, 5 have invented a new and useful Car-Coupling, of which the following is a specification, reference being had to the accompanying drawings.

This invention relates to car-couplings of that 10 class which are provided with spring-actuated arrow-headed coupling-latches that automatically effect an engagement, and can be uncoupled without going between the cars.

The invention has for its object to provide a 15 simple coupling mechanism that can be operated with convenience, and will possess superior efficiency in the performance of its functions.

In the drawings, Figure 1 is a perspective 20 view of the end of a car equipped with my improved coupling. Fig. 2 is a bottom view of the same. Fig. 3 is an end view. Fig. 4 is a vertical sectional view in detail, taken longitudinally. Fig. 5 is a vertical transverse sectional view in detail, taken through the brace- 25 plate in rear of the bumpers. Fig. 6 is a detail transverse sectional view taken through the slot in the rear end of the bumpers, on a vertical plane. Fig. 7 is a detail view, in perspective, of the bumpers of a car, with their 30 connecting and coupling mechanism.

Referring to the drawings, A designates the 35 end of a car, which is provided on its bottom with parallel beams BB, having friction-plates C on their inner faces.

D is the buffer or bumper, which is arranged 40 to slide between the beams BB, and is provided at its front end with lateral heads or extensions E E which come against the front ends of the said beams BB and limit the backward movement of the bumper. The latter is 45 retained in position by means of a transverse bolt, F, passing through the beams BB, and through a transverse longitudinally-disposed slot, G, in the rear end of the bumper, so that the same has its movement on the said bolt. A cross-piece, H, extending from one beam to the other, supports the front end of the bumper, and from the rear end of the latter extends 50 a drag-bar, I, that is supported and braced by a transverse plate or block, J, through which

it passes, the said plate being provided with a perforation, K, to accommodate the bar I. The plate J is retained from longitudinal displacement by being received into vertical grooves L 55 L in the faces of blocks M M, bolted to the inner sides of the beams BB. Vertical displacement of the plate J is prevented by means of transverse bolts N N, which pass through the beams BB and through the said plate. 60

On the bar I, between the rear end of the bumper and the plate J, is arranged a coiled spring, O, loosely encircling the said bar or rod I, the function of which spring is to break the shock when the bumper is driven back between 65 the beams BB, when the cars come together in coupling, by being compressed between the rear end of the bumper and against the said plate J. Another coiled spring, P, is loosely arranged on the rod I, between the rear side of 70 the plate J and a jam-nut, Q, adjusted on the screw-threaded rear end, R, of the rod, which spring is compressed between the said nut and the plate J to break the shock in starting. By 75 removing the said nut the springs can be removed, and the bumper can be withdrawn from between the beams BB.

S is the coupling-hook, which is pivoted in 80 a recess, T, in the front part of the bumper, and is provided with an arrow-shaped head, U, and with an extension, V, in rear of its pivot W, that engages a shoulder, X, in the bottom of the rear end of the recess T to limit downward movement of the arrow-head. This extension V is provided with a flat spring, Y, that comes 85 against the shoulder X to break the shock. A flat spring, Z, is secured at the rear end of the bumper, and projects forward from the same, so that its front end, A², bears on the hook S, in front of its pivot W, to force the same down 90 and retain it in engagement with the corresponding hook of the adjoining car.

In practice, when the coupling-hooks of the 95 cars come together they will automatically engage each other and be held in engagement by the springs Z Z. By means of this arrangement a coupling can be automatically effected between cars of varying height, and the coupling readily and automatically adjusts itself to different grades. To uncouple it is only necessary to operate either one of the levers B² B² 100 from the side of the car to raise the hook from

out of engagement with the hook of the adjoining car. These levers are fulcrumed under the beams B B, and pivotally connected to the under side of the hook S, in rear of its pivot, as shown at C², while their outer ends are adjustable in a rack, D² arranged on the end of the car.

The operation and advantages of my invention are obvious. It is simple and efficient, 10 and will infallibly and automatically effect the coupling, while it can be easily uncoupled or examined when desired.

I claim as my invention—

1. The combination, with the parallel beams B B, of the buffer or bumper arranged to slide between the same against an elastic cushion, and carrying a pivoted coupling-hook, said bumper being provided with lateral heads or extensions E E at its front end, that come 15 against the front ends of the beams B B to limit movement of the bumper, as set forth.
2. The combination of the beams B B, the bumper arranged to slide between the same, and having the transverse slot G, and the stem 20 or drag-bar I, the bolt F, passing through the beams B B and the slot G, the fixed plate J, having a perforation for the bar I, and secured between the beams B B, in rear of the bumper, by means of cross-bolts N N, the coiled spring 25 arranged on the bar I between the end of the bumper and the plate J, the coiled spring ar- 30

ranged on the bar I between the plate J and the nut Q, and the nut Q, adjusted on the screw-threaded end of the bar I, as set forth.

3. The combination of the beams B B, the bumper arranged to slide between the same, and provided with the drag-bar I, the blocks M M, secured to the beams B B, and having the vertical grooves L L, the plate J, arranged in the grooves, and having the perforation for 40 the bar I, the cross-bolts N N, passing through the beams B B and the plate J, the coiled springs O and P and the nut Q, as set forth.

4. The combination of the beams B B, the bumper arranged to slide between the same, 45 and provided with a recess, T, in its front end, having a shoulder, X, the coupling-hook pivoted in the said recess, and having the extension V, provided with the spring Y, that engages the shoulder X, the spring Z, secured to the sliding bumper, and bearing on the coupling-hook, and the operating-levers connected to the coupling-hook and fulcrumed on the fixed beams B B, as set forth.

In testimony that I claim the foregoing as 55 my own I have hereto affixed my signature in presence of two witnesses.

ISAAC L. STOVER.
